UNITED STATES PATENT OFFICE.

SIDNEY GOTTHEIL ROBERTS, OF CHATTANOOGA, TENNESSEE.

ENGINE.

Application filed March 15, 1927. Serial No. 175,634.

This invention relates to improvements in power generating apparatus, having for an object to provide a rotary engine comprehending means for receiving and delivering a motive charge into the working chamber of the engine with but a minimum of frictional resistance and without power losses therefrom.

It is also amongst the principal desiderata of the invention to provide a novel form of means for receiving the initial fuel charge, converting the same into an expandable gas and then introducing said gas into engagement with the engine rotor for imparting rotary motion thereto and thereby, developing the desired power.

Other objects of the invention will be in part obvious and in part pointed out hereinafter.

In order that the invention and its mode of operation may be readily understood by those skilled in the art, I have in the following detailed description and in the illustrative drawings based thereupon, set out one possible embodiment of my invention.

In these drawings:

Figure 1 is a vertical section through the improved apparatus showing the piston of the charge forming and delivering device in one position,

Figure 2 is a similar view wherein the piston of the charge forming and delivering device is in its uppermost position whereat the spring returning means therefor is compressed,

Figure 3 is a horizontal section taken on the line 3—3 of Figure 2 looking in the direction in which the arrows point,

Figure 4 is a fragmentary horizontal section taken on the line 4—4 of Figure 1,

Figure 5 is an enlarged fragmentary detail in section showing the construction of the valve means employed for controlling communication between the compressed air chamber and the combustible fuel supplying chamber, and

Figure 6 is a top plan view of the apparatus.

Having more particular reference to the drawings, in connection with which like characters of reference will designate corresponding parts throughout, the improved apparatus may be stated to comprise a rotor casing or housing generally indicated by the numeral 1, said casing being provided

with a suitable supporting base 2, while a water receiving and circulating jacket 3 is arranged thereabout and as will be understood, is adapted to receive and to circulate therethrough water or some other suitable cooling medium. A reversible rotary inlet valve 4 is positioned in suitable bearings adjacent the upper and intake end of the rotor casing 1 while an exhaust port or opening communicates with the way 5 at the lower portion of said casing; the inlet valve 4, obviously serving to permit of the proper introduction of a motive charge into engagement with the rotor 6 mounted within said casing 1 upon a suitable shaft 7.

A second casing generally indicated by the numeral 8 is received upon and supported by the upper end of the rotor casing 1, as is shown in the Figures 1 and 2 and is fixedly connected to said upper end of the rotor casing through the medium of connecting bolts 9 passed through appropriately flanged portions of the lower end of said second casing 8; this casing being also formed with a cooling medium receiving and circulating jacket 10 while a plurality of chambers 11 and 12 are provided therein and arranged in relatively vertical parallel relation.

That the upper end of the second casing 8 may be effectually closed, a head 13 is provided the same and, as will be understood, this head is adapted to be securely connected to said upper end of the casing 8 through the medium of bolts or other suitable fastening devices, not shown herein.

Communication is effected, at times, between the chambers 11 and 12 to ways or ports 14 and 15, the ports 14 being formed in one portion of the head 13 as is shown in the Figures 1 and 2 while the port 15 is formed in that partition or wall separating the chambers 11 and 12, adjacent their respective bottoms. Also the conduit or manifold 16 is provided the outer open end of the port 14 and is adapted to be fixedly connected thereto, said manifold having a spring actuated check valve 17 normally seated therein whereby to prevent the back flow of air or other motive fluid therethrough; a similar check valve 18 being mounted within the head 13 adjacent the point of communication between the port 14 and the chamber 12, whereby the flow of compressed air from the chamber 11 under urge of the piston working therein (herein-

after more fully described) will be permitted to discharge into the chamber 12 but will be prevented from passing therefrom at this particular point of communication.

10 A piston 19 is mounted for rectilinear movement within the chamber 11 and carries upon its upper side a longitudinally disposed hollow piston rod 20, said rod passing through a suitable packing or stuffing gland 21 provided upon said head 13 to a point exteriorly of the chamber 11; the upper and free end of the rod being shouledered and formed with a screw threaded extension adapted to receive a disk like element 22 thereupon, said element 22 being locked against displacement with respect to the screw threaded extension by means of a suitable locking nut 23 turned into engagement therewith and having bearing upon 15 the adjacent side of said element 22. Also, a packing or stuffing gland 24 is provided in the reduced and screw threaded upper end of the hollow piston rod 20, for a purpose which will be hereinafter more fully described.

20 Fixedly mounted upon the outer and upper side of the casing 13 are a plurality of vertically disposed relatively parallel standards 25 having longitudinally disposed 25 slots formed therein for the greater portions of their respective lengths and the inner sides of these slots having gear teeth 26 formed thereupon throughout their respective lengths, as is shown in the Figures 1 and 2; the lower portions of these standards being formed with feet which in turn receive connecting or securing bolts 27 therethrough in order that a fixed mounting of the standards 25 upon the casing 13 will be effected. 30 Another standard 28 is mounted upon the upper side and opposite end portion of the casing head 13, being secured to said head through the medium of a connecting bolt 29 passing through a laterally offset foot 45 thereon into engagement with an adjacent portion of said head 13; the upper end portion of this standard 28 being formed with an offset and substantially right angularly formed extension 30 having a bell crank 50 lever 31 mounted upon its free end.

55 A table or plate 32 is fixedly carried upon the upper extremities of the standards 25 and 28 and is formed with an intermediately arranged opening while upon the under side of the same, a circular rib 33 is formed, for a purpose which will be presently described.

60 Interposed between the disk like element 22 and the plate 32 is a coiled spring 34, the lower convolution of said spring being engaged with a ring like retaining device 22' formed upon the upper side of the element 22 while the upper convolution of said spring is engaged with the ring like device 33 upon the plate 32. Through the 65 arrangement of this spring 34 between the

plate 32 and the disk like element 32 carried upon the upper end of the hollow piston rod 20, it will be understood that a normally downwardly directed pressure will be transmitted to said rod 20 and its piston 19 thus, 70 tending to urge the same to its lowermost position within the chamber 11, aforesaid.

With a view toward providing a piston 19 with means for raising the same in the chamber 11 as when starting the engine, a shaft 75 35 carrying pinions on the opposite end portions thereof as indicated by numeral 36, is arranged within and transversely of the slots or ways of the uprights 25; the pinions 36 meshing with the gear teeth 26 and being 80 adapted to be rotated thereover through the medium of a crank handle 37 secured to one end of the shaft 35, while another handle or gripping device 38 is fixedly secured to an adjacent portion of the shaft 35 whereby to 85 facilitate the rotation of the crank 37 and the proper steadyng of the shaft 35 during such movement. A hooked arm 39 is pivotally carried by the shaft 35 and this arm is adapted to have engagement under an adjacent portion of the disk like element 22, in the manner as is shown in Figure 1, 90 whereby with rotary movement of the shaft 35 from the crank handle 37 in the proper direction, the pinions 36 will be caused to ascend the vertical racks 26 of the uprights 25 and consequently thereupon, to draw the said disk-like element 22 upwardly thereby compressing the coiled spring 34, hereinbefore described.

95 That communication as between the chamber 11 and the chamber receiving the rotor 6 may be controlled at predetermined times, a substantially frusto-conical valve 40 is adapted to be seated upon a valve seat 40' 100 formed in the bottom of the casing 8, as is shown in the Figure 2, whereas said valve is provided with an elongated stem 41 adapted to be extended longitudinally through an opening formed in the concentric portion of the piston 19 and through the rod 20 thereof to a position above it and through an opening formed in the plate 32. A coil spring 42 is arranged about the upper portion of the valve stem 41, having bearing upon an 105 abutment or similar stop 43 secured to the stem while the upper portion of said spring has bearing upon an adjacent part of the plate 32, hence, imparting a normally downwardly directed pressure to the valve stem 41 and consequently, serving to retain the valve 40 upon its seat 40' in the bottom of the chamber 11. Also, the upper extremity of the stem 41 is screw threaded and receives thereupon an adjusting nut 44, said 110 adjusting nut being arranged above the plate 32. A stop collar 45' is adjustably connected to the upper portion of the valve stem 41 through the medium of a set screw 46' and is adapted, at times, to be engaged 115

100

95

105

110

115

120

125

130

by the adjacent end portion of the piston rod 20, and especially, the nut of the stuffing or packing gland 24.

Trigger mechanism is provided the valve 41 for securing it in its raised position whereat the valve 40 will be held in open relation with respect to its seat 40', such mechanism consisting of a trigger or bolt 45 slidably mounted upon the upper side of the 10 plate 32 and disposed through suitable guide brackets 46 secured to said plate; the inner end of such trigger or bolt being adapted to be engaged under the adjusting nut 44, at times, while the outer or remaining end of 15 said bolt is provided with an angularly disposed finger 47 adapted to be engaged by the free or lower leg portion of the bell crank lever 31, hereinbefore described, whereby with locking of said lever 31 in one direction, 20 the bolt 45 will be slid in an outwardly direction from the stem 41 and the adjusting nut 44 thereupon; the said bolt 45 being adapted to be normally returned to its inner position whereat it will engage under the 25 adjusting nut 45, through the medium of a contractile coiled spring 48 having one end anchored to a portion of the plate 32 and its opposite end connected to said bolt 45. Thus, it will be understood that with raising of the 30 valve stem 41 and opening of the valve 40, the spring tensioned slidable bolt 45 will immediately engage under the adjusting nut 44 and hence, will prevent return vertical movement of the valve stem 41 and the valve 35 40 to closed position. However, when rocking movement, in the proper direction, is imparted to the bell crank lever 31, the free leg portion of said lever will swing in a direction to permit sliding movement of the bolt 45 under urge of the contractile coil spring 48 to a position under said adjusting nut 44, hence holding the valve 40 and its stem 41 in open position.

A control device, serving as means for effecting the starting and stopping of the improved apparatus is provided in form of a substantially bell crank lever 49 having a handle portion 50 formed on one extremity thereof while a laterally slidable bolt or pin 51 is connected or pivoted to the free leg portion of the lever and is slidably received through a suitable guide way or bracket 52 formed in the lower portion of the upright 28, the free end of the pin 52 being so arranged that it may be engaged under the disk-like element 22, by rocking such bell crank lever 40 upwardly and thus imparting inward movement of the stem 51. In this connection, it will be noted that the bell 55 60 crank lever 49 has pivotal mounting upon a suitable bracket 53, which in turn is fixedly connected to an adjacent portion of the casing head 13.

In order that a combustible fuel may be 65 delivered to the chamber 11 below the piston

19, at predetermined periods, there is secured to one side and lower portion of the casing 8, a substantially cylindrical casing or housing 54, through the medium of bolts 55 passed through appropriately flanged portions of said casing and into fixed engagement with the adjacent portions of the side wall of the casing 8, as is shown in the Figures 1 and 2. The inner portion of this casing 54 is formed with a lateral enlargement 70 56 and engaged therein is one element of an electrical circuit make and break device 57. Also, a fuel inlet pipe or manifold 58 is connected to and communicates with the interior of the casing 54, having a check valve 80 59 interposed therein whereby to prevent any back flow of fuel from the chamber of the casing 54 into said intake manifold 58.

Slidably mounted within the cylindrical chamber of the casing 53 is a piston 60 85 splined for slidable movement upon a hollow piston rod 61 extending outwardly therefrom and fixedly mounted in the walls of the chamber 12, a reduced hollow stem 62 being slidable in the outer end of the rod and connected to said piston, said stem, in turn, carrying a valve 63 thereon. A coil spring 64 is arranged about the hollow piston rod 61, having one end thereof engaging the adjacent side of the piston 60 while the opposite end thereof has bearing upon an adjacent portion of the wall of the casing 8. Thus, it will be understood that a normally outward thrust will be imparted to the piston 60 and consequently thereupon, that said piston will be normally held adjacent to the head of the cylinder chamber. A second make and break circuit closing element 65 is fixedly connected to one portion of the piston 60 and is adapted, at times, to be engaged 100 with the element 57, hereinbefore described, also, the end of the cylindrical casing 54 is provided with a movable head, preferably in form of a piston like element 66 slidably arranged in the outer end of the chamber 110 of said cylinder and secured to a screw threaded rod 67 passing through an internally screw threaded opening in the outer end wall of said casing 54 whereat it is provided with a suitable form of handle 68. 115 Thus, by rotating the screw threaded rod 67, the positioning of the head 66 may be varied with respect to the piston 60.

That the stem 62 of the valve 63 may have a pulling movement imparted thereto, whereby the piston 60 may be moved in a direction to effect an intaking of fuel into the chamber of the cylindrical casing 54 and that the valve 63 may be moved from its seat 69 formed in the lower portion of the wall separating the chambers 11 and 12, a lever 70 is provided, said lever being pivotally connected as at 71 to the outer end of the valve stem, while one end thereof is formed with a bearing device 72 and the opposite end there- 125 130

of with a curved finger like extension 73 adapted to have fulcruming engagement with an adjacent portion of a corresponding side wall of the chamber 11.

6 Also, it will be noted in this connection, that a spherical spring pressed check valve 74 is seated within the valve 63 and normally serves to close the outer end of the longitudinal passage way through the stem or extension 62, hence, controlling the communication of said way with the interior of the chamber 11.

15 A spark plug or other suitable ignition means indicated by the numeral 75 is adapted to be engaged in the lower portion of the chamber 11, whereby, with the introduction of a properly carbureted and compressed fuel into said chamber, the same may be exploded at a predetermined time 20 for imparting a working impulse to the piston 19.

That overloading or stressing of the casing 8 by an excessive pressure within the chamber 11 may be avoided, a safety valve 25 or similar device 76 is engaged with one portion of the casing 8 and has communication with said chamber 11.

In operation of my improved apparatus, the disk like element 22 is engaged by the 30 hooked pivotal arm 39 whereupon the crank handle 37 is rotated to effect ascension of the pinions 36 with respect to the rack bars 26 of the uprights 25. As the disk-like element 22 passes the inner end of the bolt or 35 slide pin 51, the handle 50 thereof is moved in a direction to cause the inner extremity of said pin to be arranged in the normal path of downward movement of said element 22. Rotation of the pinions 36 is continued, thereby raising the disk like 40 element 22 together with the piston rod 20 and the piston 19 and simultaneously, compressing the coiled spring 34. Rotation of these pinions is continued until the piston 19 and the disk like element 22 assumes 45 those positions as shown in the Figure 2, with the exception that said disk-like element is not raised sufficiently to effect contact as between the stuffing gland 24 thereby 50 carried and the adjustable stop collar 45'. During upward movement of the piston 19 in its chamber 11, it will be understood that air within the upper portion of said chamber 11 would be compressed and will be 55 discharged by way of the passage 14 in the casing head 13 by the spring pressed check valve 18 into the compressed air storage chamber 12. With the piston thus raised to a position in proximity to the top of the 60 chamber 11, the crank handle 37 is now permitted to rotate in an opposite direction under urge of the compressed spring 34, which, as will be understood, directs a downward stress onto the disk-like element 22 and 65 the piston 19 together with the piston rod 20.

Said disk-like element will descend until it engages with the inner end of the slideable pin 51, at which time, it will be understood that the piston 19 within the chamber 11 is immediately above but in contact with the bearing device 72 of the fulcruming lever 70. To start the apparatus, the pin 51 is disengaged from the under side of the disk-like element 22 by rocking the handle 50 downwardly. At this time, the still compressed coiled spring 34 will impart a stop or abrupt downward movement to the piston 19 within its chamber 11, causing its piston to engage with the bearing end or device 72 of the fulcruming lever 70, whereby said lever will function to impart a pull to the valve 63, the stem 62 and the piston 60. Movement of this piston 60 under this influence will draw a charge of combustible fuel into the base or chamber between said piston 60 and the adjustable head 66, while at the same time, inasmuch as the valve 63 is removed from its seat 69, compressed air stored within the chamber 12 will be permitted to rush into the lower portion of the chamber 11 and to engage the lower side of the piston 19, thus forcing the same upwardly for a slight distance, this vertical movement of the piston 19 being sufficient to effect its disengagement from the bearing end 95 of the fulcruming lever 70, whereupon the valve 63 and the piston 60 will abruptly return to their normal positions under influence of the expansible coiled spring 64. With abrupt outward movement of the piston 60 in the chamber of the casing 54, the charge of combustible fuel previously taken thereinto will be forced through the hollow piston rod and the extension or stem 62 by the check valve 74 into the lower portion of the chamber 11 below the piston 19 and simultaneously with the discharge of this combustible fuel into the lower portion of said chamber 11, the make and break circuit closing elements 57 and 65 will engage with each other, thus closing an electrical circuit to the igniting device 75, producing a spark in the combustion chamber and thereby exploding the fuel within the same and imparting an upward working 100 thrust to the piston 19, passing said piston upwardly within the chamber 11 to its uppermost position whereupon the upper end of the piston rod 20, and especially, the stuffing or packing gland 24 thereof will 105 engage with the stop collar 45' secured to the elongated valve stem 41, hence imparting an upward movement to said valve stem and removing the valve 40 from its seat 40'. With movement of the valve 40 from its seat 110 40', it will be noted that the adjusting nut 44 carried upon the upper end of the valve stem 41 will be raised above the inner end of the spring pressed slideable bolt 45 so that 115 such bolt under urge of the spring 48 will 120

75

80

85

90

95

100

105

110

115

120

125

130

immediately engage beneath the same and hence, prevent the immediate closing of the valve 40 to its seat 40'. The piston 19 having completed its upward movement or 5 working stroke, now starts to descend in the chamber 11 under urge of the compressed coil spring 34. In this movement of descent, the exhaust gases created from the explosion of fuel within the chamber 11 below 10 said piston 19 will be compressed and will be forced through the valve seat 40' into engagement with the peripheral vaned surface of the rotor 6 mounted within the rotor casing, thus imparting rotary motion there- 15 to. As the disk-like element 22 descends with the piston 19 and its rod 20, a portion of said element 22 will engage with an adjustable abutment 77 carried upon a trp rod 78, the upper or free end of which is pivotally connected to the adjacent end of the bell 20 crank lever 31, thereby rocking said bell crank lever in a direction to cause retraction of the slideable bolt 45 from the adjusting nut 44 upon the upper end of the valve 25 stem 41 and consequently, permitting said valve stem together with the valve 40 to be immediately returned to closed position under influence of the compressed coiled spring 42, whereupon the cycle of operation 30 is repeated.

Obviously, should it be desired to stop the apparatus, the handle 50 is rocked in a direction to cause the slideable bolt 51 to be movable to a position to engage with a 35 portion of the under side of the disk like element 22 as the same descends. At the time of such engagement, it will be understood that the piston 19, while being in immediate proximity to the bearing device 72 40 of the fulcruming lever 70 will not be in contact therewith and hence, will be prevented from rocking said lever and causing movement to be imparted to the valve 63, the stem 62, and the piston 60, thus interrupting the supply of compressed air to the 45 chamber 11 from the chamber 12 and also, the supply of combustible fuel from the cylindrical casing 54 by way of said stem 62 into the lower portion of the chamber 11.

50 Manifestly, the construction shown is capable of considerable modification and such modification as is within the spirit of my claims, I consider within the scope of my invention.

55 I claim:

1. A device of the character described comprising in combination, a rotor receiving casing, a second casing above and in longitudinal alignment with the first casing having a pair of juxtaposed coincidingly disposed communicable chambers therein, a piston received in one of said chambers, spring means carried by said second casing and arranged exteriorly thereof engaged 60 with said piston for normally imparting a

downwardly thrust thereto, valve means for controlling communication between said piston receiving chamber and the rotor casing, adjustable means engageable by the rod of said piston for effecting operation of said valve means, and means adjacent the remaining chamber operable by said piston for effecting a forced discharge of fuel into the lower portion of the piston receiving chamber. 70

2. A device of the character described comprising in combination, a rotor receiving casing, a second casing above the first casing having a pair of juxtaposed relatively parallel and longitudinally disposed communicable chambers therein, a piston received in one of said chambers, spring means carried without said second casing and having engagement with the rod of said piston whereby to impart, a starting downward thrust thereto, valve means for controlling communication between such piston receiving chamber and the rotor casing; adjustable means engageable, at times, by the rod of piston for effecting operation of said valve means, means adjacent the remaining chamber for effecting a discharge of a predetermined amount of fuel into the lower portion of the piston receiving chamber, and valve means cooperable with said last mentioned means and operable by said piston immediately prior to the finish of its downward stroke. 85

3. A device of the character described, comprising in combination, a rotor receiving casing, a second casing supported above the first casing, having a plurality of relatively parallel juxtaposed and communicable chambers therein, a piston received in one of said chambers, manually operable spring means carried on said second casing exteriorly of the same for imparting, a starting downwardly directed thrust to said piston, valve means for automatically controlling communication between said piston receiving chamber and the rotor casing operable by said piston, means engageable with said valve means subsequently to opening of the same by said piston for retaining such valve means in open position for a predetermined time, and means operable by said piston immediately prior to the finish of its downward stroke for effecting the discharge of a predetermined amount of fuel into the lower portion of the piston receiving chamber. 100

4. A device of the character described comprising in combination, a rotor casing, a rotor therein, a second casing supported above the first casing having a pair of relatively parallel communicable chambers therein, a piston received in one of said chambers, spring means on the second casing exteriorly thereof engaging the rod of said piston for imparting, at times, a downward 105 110 115 120 125 130

thrust to said piston, manually operable means for raising the piston within its chamber and compressing said spring means, valve means for controlling communication between said piston receiving chamber and the rotor casing, means carried by the piston and cooperable with said valve means for effecting operation thereof at a predetermined time, other means engageable with said valve means for holding the same in open position during certain movement of said piston within the chamber, manually operable means for limiting the extent of downward movement of said piston in its chamber and controlling operation of the device, another chamber secured to and communicable with said second casing, a fuel inlet means communicating with said last mentioned casing, a piston working within said last mentioned casing, a valve stem extension carried on the outer end of the rod

of said last mentioned piston, a valve on said stem for controlling communication between the chambers within said second casing, valve means also within said stem for controlling communication between the piston receiving chamber and the interior of said last mentioned casing, charge igniting means in the lower portion of the piston receiving chamber, electrical circuit make and break means operable by movement of the piston within said last mentioned casing, and means movably connected to the inner end of said stem and arranged within the lower portion of the piston receiving chamber adapted to be engaged by said piston whereby to effect movement of the valve carried by said stem and simultaneous movement of the piston within said last mentioned casing.

In witness whereof I have hereunto set my hand.

SIDNEY GOTTSEELIG ROBERTS.
